RAZOR BLADE SHARPENER
George E. Dietze, 1942 Lakeside Drive, Erie, Pa.
Filed Jan. 5, 1962, Ser. No. 164,527
6 Claims. (Cl. 51—205)

This invention is a sharpener for safety razors which can be used on existing razors and which does not require removal of the blade for sharpening. The sharpener is merely placed on the cap plate of the razor and moved longitudinally of the blade edge after the sharpening elements have been moved into engagement with the upper and lower sides of the blade edge. Only two or three strokes of the sharpener are required so that the sharpening operation is completed in less time than changing blades.

In the drawing, FIG. 1 is an end elevation of the sharpener mounted on a Gillette type safety razor, FIG. 2 is a bottom plan of the sharpener, FIG. 3 is an enlarged fragmentary view showing the sharpening elements in position, FIG. 4 is an enlarged fragmentary end view illustrating the sharpening action, and FIG. 5 is a section through one of the plungers.

The sharpener can be made for any safety razor, single edge or double edge. The particular sharpener shown is for the Gillette type razor which comprises a head 1, a cap plate 2, and a handle 3 for tightening the cap plate against the blade 4 and positioning the cutting edges 4a of the blade in shaving relation to the underlying guard 5. The particular shaver shown has an adjustment 6 which moves the guard 5 up and down relative to the cutting edges 4a to vary the closeness of the shave. The sharpener, however, is not limited to the particular Gillette type razor illustrated, but is applicable to all Gillette type razors, even the old style three piece models where the cap plate 2 is made in one piece. Since Gillette type razors are well known, the construction need not be described further.

The sharpener is used with the blade mounted in shaving position in the razor. No adjustment of the razor is necessary. Whenever it is discovered that the blade is dull, both edges may be quickly sharpened by two or three strokes without removing the blade from the razor. The entire sharpening operation requires less time than changing blades.

The sharpener has a frame 7 conveniently made as a casting with an arcuate underside 8 which fits over the cap plate 2. Fixed to the frame at opposite edges of the underside of the frame are blocks 9a having grooves or guides 9 which slidably ride on the outer edges 10 of the cap plate. The purpose of the grooves 9 is to position the sharpener. Since the outer edges 10 of the cap plates are of fixed and standard dimensions, the edges 10 and the adjacent upper surface 11 of the cap plate serves as an accurate guide for the sharpener holding it in fixed relation to the cutting edges 4a. The grooves 9 provide an easy sliding fit so that the sharpener may be slid lengthwise back and forth over the cap plate. On opposite sides of the sharpener frame are plungers 12, having finger pieces 13 at the outer ends and having the inner ends engaging opposite ends of a coil spring 14 and urging the plungers outward. The coil spring 14 fits in a groove 15 on the under side of the sharpener frame and the opposite ends enter sockets 16 and urge the plungers outward. In the outer position of the plungers, wedge shaped sharpening members 17 fixed to the under sides of the finger pieces 13 are spaced outward away from the edges 4a of the blade so there is no contact with the cutting edges when the sharpener is mounted on the cap plate 2. The plungers 12 and the sockets 16 are provided with complementary keying means 18, preventing turning of the plungers relative to the sharpener frame so that the sharp-

2

ening members 17 are held strictly parallel to the under side of the blade edges. The sockets 16 and the plungers 12 are provided with suitable stops (not shown), limiting the movement of the plungers in both directions.

5 The sharpening action is illustrated in FIG. 4 which is a highly magnified fragmentary end view. As there shown, the blade 4 is clamped against the under side of the cap plate 2 which is slidably received in grooves 9 in blocks 9a on the sharpener. The blade has a roughly 10 sharpened section 20 having upper and lower sides 21, 22 which include a small acute angle and a finely sharpened section 23 having upper and lower sides 24, 25 which include a larger acute angle. The intersection of the sides 24 and 25 provides the cutting edge 4a. In all Gillette type razors, the sides 24 and 25 which define the cutting edge 4a are in fixed relation to the edge 10 of the cap plate 2 on which the sharpener is guided. When the sharpener is mounted on the cap plate, the smooth under surfaces 27 of the blocks 9a match the upper sides 24 of the blade edges. When the plungers 12 are moved inward, the smooth upper surfaces 28 of the sharpening elements 17 match the lower sides 25 of the blade edges. In order to insure contact between the blade edge 4a and the sides 27 and 28, the included angle between the sharpening surfaces 27 and 28 is slightly greater than the included angle between the sides 24 and 25. This insures contact at the edges 4a. The blocks 9a and the sharpening elements 17 are in staggered relation so that each complements the other in supporting the blade edges. The surfaces 27 of the blocks 9a rest lightly on the upper side of the blade edge while the surfaces 28 of the sharpening elements 17 engage lightly the lower side of the blade edge and as the sharpener is moved back and forth lengthwise of the cap plate 2, the surfaces 24 and 25 of the blade edge 4a are brought into sharpened relation with a honing or stropping action. Any material suitable for sharpening may be used for the blocks 9a and sharpening members 17. The surfaces 27 and 28 should be hard enough to hone the surfaces 24 and 25 of the blade edges. Hardened steel is a suitable material. Glass or a fine abrasive is also suitable, although somewhat more difficult to mount on the sharpener.

40 When it is discovered that the blade edges require sharpening, the sharpener is mounted on the cap plate 2 of the razor and the plungers 12 are moved inward by pressure exerted on the finger pieces 13. This moves the sharpening elements 17 between the guard 5 of the razor and the under side of the blade edges and establishes the cooperative engagement with the blade edges and the surfaces 27 and 28 so that as the sharpener is moved back and forth along the cap plate two or three times, the original sharpness of the blade edges is restored. The sharpener may be used at any time, even during shaving and the entire sharpening operation from start to finish 45 requires less time than changing blades.

50 The sharpener shown fits all Gillette type razors. Other sharpeners can be made to accommodate any other type of razor having a blade held against the under side of a cap plate and with a cutting edge spaced above a guard.

55 If the sharpening elements 17 are omitted, surfaces 27 will sharpen the upper side of the cutting edge 4a. This provides adequate sharpening although it may be necessary to turn the blade over after several days of sharpening only the upper side of the cutting edge.

60 65 What is claimed as new is:

1. A sharpener for sharpening a safety razor blade while mounted on a safety razor having a cap plate with a longitudinal edge engaging the upper side of the blade inward of the cutting edge and a guard spaced below the lower side of the cutting edge comprising, a frame having a guide slidably engaging said longitudinal edge of the cap plate and guiding the frame for movement

along said longitudinal edge, said frame having thereon a downwardly presented sharpening surface engaging the upper side of the cutting edge, a sharpening element mounted on the frame for movement relative to the frame from an outer position clearing the cutting edge to an inner position extending between the guard and the under side of the blade and having an upwardly presented sharpening surface in staggered relation to said downwardly presented sharpening surface and engaging the under side of the cutting edge, said surfaces honing the cutting edge as the frame is slid back and forth along the longitudinal edge of the cap plate.

2. The construction of claim 1 in which the razor blade is double edged with the cap plate having two longitudinal edges respectively spaced inward from one and the other of the edges of the blade and the sharpener frame has two guides respectively slidably engaging one and the other of the edges of the cap plate and the downwardly presented surfaces on the frame and sharpening elements are duplicated to sharpen both edges of the 20 blade.

3. A sharpener for safety razors having a cap plate with a longitudinal edge engaging the upper side of the blade inward of the cutting edge and a guard spaced below and underlying the cutting edge comprising a frame removably mounted on the cap plate and having a guideway complementary to said longitudinal edge of the cap plate, longitudinally spaced sharpening elements on the frame having downwardly presented surfaces engaging the upper side of the cutting edge, a plunger in the frame carrying at its inner end a sharpening element receivable between the blade and guard and between the sharpening elements on the frame and having an upwardly presented surface engaging the lower side of the cutting edge, said surfaces conforming with the cutting edge and honing it as the frame is slid back and forth along the cap plate.

4. A sharpener for double edge safety razors having a cap plate with spaced longitudinal edges engaging the upper side of the blade inward of the cutting edges and a guard spaced below and underlying the cutting edges comprising, a frame removably mounted on the cap plate and having guideways complementary to the longitudinal edges of the cap plate, sharpening elements on opposite sides of the frame having downwardly presented surfaces respectively engaging the upper side of each of the cutting edges, plungers on opposite sides of the frame each carrying at its inner end a sharpening element for association with the cutting edge on its side of the frame and receivable between the blade and guard and having an upper surface engaging the lower side of the associated cutting edge, said surfaces conforming with the cutting

edge and honing it as the frame is slid back and forth along the cap plate.

5. A sharpener for double edge safety razors having a cap plate with spaced longitudinal edges engaging the upper side of the blade inward of the cutting edges and a guard spaced below and underlying the cutting edges comprising, a frame removably mounted on the cap plate and having longitudinally spaced blocks over each of the longitudinal edges of the cap plate, the blocks having guideways complementary to the underlying longitudinal edges of the cap plate and having a downwardly presented surface engaging the upper side of the cutting edges, plungers in opposite sides of the frame each carrying at its inner end a sharpening element, spring means biasing the plungers outward to a position in which the sharpening elements clear the cutting edges of the blade, the plungers being movable inward to a position, said downward and upwardly presented surfaces being in staggered relation to said downwardly presented surface and engaging the under side of the cutting edge, said surfaces honing the cutting edge as the frame is slid back and forth along the longitudinal edge of the cap plate.

6. A sharpener for safety razors having a cap plate with a longitudinal edge engaging the upper side of the blade inward of the cutting edge and a guard spaced below the lower side of the cutting edge comprising, a frame, a sharpening member on the frame having a guideway riding on the longitudinal edge of the cap plate and having a downwardly presented surface engaging the upper side of the cutting edge, a plunger guided in the frame and having on its inner end a sharpening element, spring means biasing the plunger to an outer position in which the sharpening element clears the cutting edge, a finger piece on the outer end of the plunger for moving it inwardly to a position in which the sharpening element extends between the guard and the under side of the blade, said sharpening element having an upwardly presented surface engaging the under side of the cutting edge, said surfaces honing the cutting edge as the frame is slid back and forth along the cap plate.
